UNITED STATES PATENT OFFICE.

ELLIS J. WOOLF, OF MINNEAPOLIS, MINNESOTA, ASSIGNOR TO WOOLF
VALVE GEAR CO., OF MINNEAPOLIS, MINNESOTA, A CORPORATION OF
MINNESOTA.

EXPLOSIVE-ENGINE.

No. 824,896.

Specification of Letters Patent. Patented June 26, 1906.

Application filed May 5, 1904. Serial No. 206,463.

To all whom it may concern:

Be it known that I, ELLIS J. WOOLF, a citizen of the United States, residing at Minneapolis, in the county of Hennepin and State of Minnesota, have invented certain new and useful Improvements in Explosive-Engines; and I do hereby declare the following to be a full, clear, and exact description of the invention, such as will enable others skilled in the art to which it appertains to make and use the same.

My invention relates to explosive-engines, and has for its object to provide certain important improvements therein with a view of securing increased efficiency; and to this end my invention consists of the novel devices and combinations of devices hereinafter described, and defined in the claims.

Some features of the engine herein disclosed are disclosed and broadly claimed in my prior patent No. 683,886, of date October 1, 1901.

My invention is illustrated in the accompanying drawings, wherein like notations refer to like parts throughout the several views. In said drawings, Figure 1 is a view chiefly in end elevation, but with some parts shown in section, some parts broken away and others removed, showing an explosive-engine constructed in accordance with my invention. Fig. 2 is a vertical section on the line $x^2 x^2$ of Fig. 1 or in the plane of the crank-shaft axis. Fig. 3 is a vertical cross-section on the line $x^3 x^3$ of Fig. 2. Fig. 4 is a horizontal cross-section on the line $x^4 x^4$ of Fig. 3. Fig. 5 is a horizontal cross-section on the line $x^5 x^5$ of Fig. 3, and Fig. 6 is a horizontal cross-section on the line $x^6 x^6$ of Fig. 2.

Three castings (marked, respectively, 1, 2, and 3) are rigidly secured together with suitably-packed joints. Said castings 1 and 2 part at center of the crank-shaft bearings and support a triple crank-shaft 4, provided with a flywheel 5. The casting 2 is provided with an explosion-cylinder 6, having the admission-port 7 and exhaust-port 8.

In the common explosion-cylinder 6 work a pair of opposing pistons, the upper member of which is marked 9 and controls the admission-port 7. The said upper piston 9 is provided with a cross-head pin 10, the projecting ends of which are connected by rods 11, one to each of the outer members of the

three cranks on the shaft 4. The upper casting 3 is of the proper shape to afford a pair of segmental guides 12 for the upper end portion of the upper piston 9, with clearance between the two for the outward passage of the cross-head pin 10 and to incase and afford the necessary clearance for the action of said cross-head pin 10 and its connecting-rods 11. The casting 2 is of the proper form for co-operation with the casting 3 to incase and afford clearance for the connecting-rods 11 and for co-operation with the base-casting 1 to incase the cranks of the shaft 4. The casting 2 also affords a water-jacket space c surrounding the explosive-cylinder. The other opposing piston is differential and encircles crank-shaft 4, with its upper or smaller member 13 working in said common explosion-cylinder 6 and controlling the exhaust-port 8. The said smaller member 13 of said differential piston is connected by four suitably-spaced rods 14 with its differential or larger member 15, which works in a cylinder 16, formed in the base-casting 1. The said larger member 15 is provided with a cross-head pin 17, connected by rod 18 with the central member of the three cranks on the shaft 4. Said central crank is directly opposite or one hundred and eighty degrees apart from the outer pair of co-operating cranks on the said shaft, which are connected by the rods 11 to the upper or other opposing piston 9. The two opposing pistons, it will thus be seen, are connected to opposing cranks from opposite sides of the crank-shaft.

It must be understood that the rods 14 are only one convenient means for connecting the two members 13 and 15 of the differential piston and that any other suitable construction could be employed, such as a single casting connecting the said members and cut away to afford the necessary clearance to pass and encircle the crank-shaft.

The castings 1, 2, and 3, are of such construction that the two opposing pistons, mounted as described, divide all the interior space outside the explosion-cylinder, exhaust port, and water-jacket into two chambers, and which, respectively, serve as a compression-chamber A and a lubricating-chamber B. The said compression-chamber A partly encircles the differential cylinder 16 and communicates with the lower open end of said cyl-

inder below the differential piston 15 and is provided with a charging-passage *a*, leading to the admission-port 7 of the explosion-cylinder 6. The said compression-chamber A is provided with a suitable inlet-valve 19 for the explosive mixture (shown as of the Lunkheimer type) and is located at the compressing end of said charging-passage *a*. The admission-port 7 of the explosion-cylinder is a part of the charging-passage *a*, leading from the compression-chamber A, and is provided at a point therein most remote from the mixture-inlet valve 19 with an adjustable air-admission valve 20, adapted to admit air alone to the outer end of the charging-passage coincidently with the drawing in of the explosive mixture into the compression-chamber A through said mixture-inlet valve 19, thus causing a column of air to be engaged within said charging-port for admission to the explosion-cylinder in advance of the explosive mixture, for purposes which will later more fully appear in tracing the operation of the engine. A hand-controlled governing-valve 21 is located in the charging-port *a*, directly inward of the mixture-inlet valve 19, in position to throttle either the passage from said inlet-valve to the compression-chamber or to throttle the charging-passage *a*, leading from the compression-chamber A to the admission-port 7 of the explosion-cylinder. Having regard to the other or so-called "lubricating-chamber" B, it is sufficient to note at this place that the same is in communication with all the interior working parts of the engine and is completely separated from said compression-chamber A.

The exhaust-port 8 completely encircles the explosion-cylinder 6 and is fitted with an exhaust-pipe 22. The explosion-cylinder 6 is provided with a suitable magnetic sparking-plug 23 with its pair of electrodes located in an electric circuit (not shown) and intended to be supplied with current from any suitable source. Said explosion-cylinder 6 is also shown as provided with an ordinary relief-cock 24.

The water-jacket space *c* is provided with a suitable overflow-pipe 25.

A stand-pipe 26 is suitably supported so as to be partly above and partly below the water-supply level and is provided at its lower end with a pair of check-valves 27 and 28 for controlling the flowage through the water-circulating system. The stand-pipe 26 is provided with an inflow-pipe 29, below the water-supply level, and with circulating or distributing pipes 30, leading to the water-jacket space *c* of the explosion-cylinder 6. One section of the distributing-pipes 30 is provided with a hand-controlled throttle-valve 31, for regulating the amount of the flowage, and is also provided with an air-reservoir 32 for cushioning the action and making the flowage continuous under the impulses

imparted from the stand-pipe, as will later more fully appear. The upper end portion of the stand-pipe 26 is in communication through pipe 33 with the small port 34 in the explosion-cylinder 6, controlled, as shown, by the upper member 9 of the two opposing pistons, in virtue of which connections fluid from the explosion-cylinder will be admitted to the stand-pipe and subsequently exhausted therefrom with the exhaust from the engine, which actions render the said fluid operative to force the water from the stand-pipe through the circulating system for cooling the engine.

Operation: All the parts have now been specified, and the actions of more or less thereof are probably clear from the detail description. It may be serviceable, however, to summarize the operation of the engine, first considering the distribution of the gases, then the distribution of the cooling-water, and, finally, the distribution of the lubricating-oil. Under the upper or suction stroke of the differential piston the explosive mixture will be drawn in through the inlet-valve 19 into the compression-chamber A, and at the same time air alone will be drawn through the air-admission valve 20 into the upper end portion of the charging-passage *a*, thereby filling said charging-passage with a column of air, which becomes engaged therein between the explosive mixture and the admission-port 7 of the explosion-cylinder 6. Otherwise stated, the chest of the admission-port 7 is a part of said charging-passage *a*, and the engaged column of air will occupy the same and be admitted to the cylinder in advance of the explosive mixture. On the return or downward stroke of said differential piston the explosive mixture within the compression-chamber A will be compressed and forced upward behind the engaged column of air within the said charging-passage, thereby also compressing the engaged air to the same pressure. The two opposing pistons move outward coincidentally in respect to the center of the explosion-cylinder 6, and it follows that under the outward or compressing stroke of the differential piston its smaller member 13 will uncover the exhaust-port 8, and the outward movement of the upper or other opposing piston 9 will uncover the admission-port 7, and these actions are so timed in respect to each other that the exhaust-port 8 will open shortly in advance of the admission-port 7, thereby permitting the exhaust to be under way before the admission begins. When the admission-port 7 is uncovered by the piston 9, the engaged column of air is admitted to the explosion-cylinder first or in advance of the explosive mixture, which follows from the compression-chamber A. The ports 7 and 8 both entirely encircle the explosion-cylinder 6, and the head of the smaller member 13 of the differential piston

is of cup shape or recessed, so as to make the same act as a deflector for the incoming charge. Owing to the form of said ports 7 and 8, the incoming charge enters from all sides in an even sheet, moving on convergent radial lines through the admission-port 7, directly under the flat head of the piston 9, and the spent gases exhaust outward in an even sheet from all sides through the exhaust-port 8. The incoming charge thus entering on radial convergent lines through the admission-port 7 will meet at the axial center of the explosion-cylinder 6 directly under the flat head of the piston 9 and will be deflected downward by the said piston through the central zone of the explosion-cylinder until it meets the head of the opposing piston 13 at the central portion thereof, whereupon the said central column of the incoming charge will be deflected outward and upward by said piston 13, so as to form an intermediate column encircling the down-moving central column and moving upward until it meets the radial sheet of the incoming charge still entering through the port 7, whereupon said intermediate column will be redeflected outward and downward in the outer zone or adjacent to the walls of the explosion-cylinder, all as indicated by the arrows in Fig. 2 of the drawings. Owing to the courses of travel thus taken by the incoming charge, as above described, it must be obvious that the spent gases are first centrally separated by the incoming charge and thereafter are successively forced outward and downward until the exhaust is made complete. The explosion-cylinder, including its clearance-space, is thus thoroughly scavenged, and this is done by encaged column of air entering from the charging-port in advance of the explosive mixture, thus avoiding any waste of the explosive mixture through the exhaust and always keeping a body of air between the exhausting gases and the effective charge of the incoming explosive mixture, thereby preventing either premature or back explosions. Under the return or inward movements of the opposing pistons the cylinder-ports will all be covered and closed by the pistons, and the charge will be compressed to the proper degree and at the right instant will be ignited by spark from the plug 23, thus effecting the explosion and producing the working strokes of the two opposing pistons.

The regulation of the speed of the engine is controlled by the governing-valve 21, hitherto noted, which may be made to throttle either the inlet-passage leading from the mixture-inlet valve 19 to the compression-chamber A, or to throttle the charging-passage *a* at a point directly above the said mixture-inlet valve 19.

The location of the mixture-inlet valve 19 at the compressing end of the charging-passage *a*, which has the admission-valve 20 at

the outer end thereof, is a feature of importance for insuring perfect vaporization of the explosive mixture through the inlet-valve 19, and the said governing-valve 21 also co-operates with the said inlet-valve 19 in securing this result. This disposition of said parts causes the fresh mixture drawn in through the inlet-valve 19 to meet and cross the column of old mixture drawn back from the charging-passage *a* at and around said inlet and governing valves 19 and 21, thus securing thorough commingling and vaporization of the two columns of mixture. By actual usage I have demonstrated the efficiency of said described relation of said inlet-valve 19 to the charging-passage *a*, equipped with the air-admission valve 20 and co-operating, as described, for securing the good results in respect to vaporization above set forth.

In comparing the engine herein disclosed with the engine disclosed in my prior patent, No. 683,886, of date October 1, 1901, it should be noted that the upper piston 9 acts as a charging-valve for controlling the admission-port 7 to the explosion-cylinder 6, that the compression-chamber A corresponds to the compression-chamber 4 beneath the larger member of the differential piston 6 of said prior patent, and that the mixture-inlet valve 19 and the air-admission valve 20 in the present application operate under the control of the compression end of the differential piston, all on the same principle as in my said prior patent. Said chamber 4 in my prior patent and said chamber A in the present case might very properly be called "charging-chambers."

Respecting the distribution of the strains from the explosions, it follows from the fact that the opposing pistons are connected to opposing cranks from opposite sides of the crank-shafts, as hitherto described, that all of said strains from the explosion will be equally distributed on the crank-shaft and the other working parts of the engine, thus affording a balance action throughout.

Having now regard to the distribution of the cooling-water, the small port 34 of the explosion-cylinder, connecting, through pipe 33, with the water stand-pipe 26, as described, is so located that the same will be uncovered by one of the opposing pistons, this, as shown, being the upper piston 9, shortly before the exhaust-port 8 begins to be uncovered by the opposing piston 13, and from this disposition of said parts it follows that gas from the explosion-cylinder, at or near its final or expanded pressure, will be admitted into the water stand-pipe 26 and become effective to force the water past the check-valve 28 and through the circulating system, including the water-jacket space of the explosion-cylinder and the overflow-pipe 23, and it further follows that when the exhaust-port 8 is uncovered by the piston mem-

ber 13 the gas in the stand-pipe 26 will be exhausted therefrom along with the exhaust of the engine, and thereupon the inlet check-valve 27 of the stand-pipe will open 5 under the water-supply pressure and the effect of any partial vacuum created in said stand-pipe by the cooling of the gas left therein after the port 34 was closed, thus permitting the stand-pipe again to refill to its 10 original level. The presence of the air-reservoir 32 cushions the action and makes the flowage through the circulating system continuous under the impulses intermittently imparted to the water from the stand-pipe. 15 The throttle-valve 31 enables the quantity of the water-flowage to be regulated at will. The said stand-pipe and connections described thus enable the required cooling-water to be circulated by direct pressure from 20 the explosion-cylinder itself and constitute an extremely simple and efficient means for accomplishing this result.

Having regard now to the distribution of the lubricating-oil, it should first be noted 25 that the displacement effected by the differential or larger piston 15 within the lubricating-chamber B, under the dimensions shown, is twice as great as the combined displacement effected by the piston members 9 and 30 13, and hence it follows that the body of air within said lubricating-chamber B will move or flow under a pulsating action throughout 35 all the channels or spaces available for the flowage or compression thereof. The differential or larger piston 15 is of cup shape on its upper face, thus affording a receptacle for the lubricating-oil, and under the reciprocating motion of said piston the oil will be thrown upward into the pulsating body of 40 air, and sufficient thereof will be carried by the air into contact with the working parts of the engine to furnish an abundance of oil thereto for the required lubrication thereof. Otherwise stated, the oil and air within the 45 lubricating-chamber B are, when the engine is in motion, continuously subject to the action of all the cranks and all the pistons and the oil to a dashing action through the pulsating air, with the result that all parts of the 50 engine will be thoroughly lubricated therefrom.

The lubricating-oil is supplied to the chamber B through a suitable filling-plug 35, provided for the purpose in the base-casting 1.

55 The volume capacity of the lubricating-chamber B is so great that the differential displacement produced by the larger piston 15 results only in a very low compression therein, under dimensions shown, and, moreover, any power consumed in effecting the compression within the lubricating-chamber B under the compression-stroke of the differential piston within said lubricating-chamber will be given back to the said piston during 60 its return or expansion stroke.

The organization herein disclosed constitutes a balanced, highly-efficient, and comparatively noiseless two-cycle engine of extremely simple construction.

It will be understood, of course, that modifications may be made in the construction without departing from the spirit of my invention.

What I claim, and desire to secure by Letters Patent of the United States, is as follows: 75

1. In a two-cycle explosive-engine, the combination with an explosion-cylinder and a charging-valve controlling the admission of the explosive mixture thereto, of a differential piston encircling the crank-shaft, the 80 smaller member of which differential piston works in said explosion-cylinder, and controls the exhaust-port, and the larger member of which works in a charging-cylinder on the opposite side of the crank-shaft, and is connect- 85 ed thereto, substantially as described.

2. In a two-cycle explosive-engine, the combination of a pair of opposing pistons working in a common explosion-cylinder, one controlling the exhaust-port and the 90 other the admission-port of said cylinder, and one of which pistons encircles the crank-shaft, and which two opposing pistons are connected to opposing cranks from opposite sides of the crank-shaft, substantially as de- 95 scribed.

3. In a two-cycle explosive-engine, the combination of a pair of opposing pistons working in a common explosion-cylinder, one controlling the exhaust-port and the other 100 the admission-port of said cylinder, and one of which pistons is differential and encircles the crank-shaft, and which two opposing pistons are connected to opposing cranks from opposite sides of the crank-shaft, substantially 105 as described.

4. In a two-cycle explosive-engine, the combination of a pair of opposing pistons working in a common explosion-cylinder, one controlling the exhaust-port and the 110 other the admission-port of said cylinder, one of which pistons is differential and encircles the crank-shaft, which two opposing pistons are connected to opposing cranks from opposite sides of the crank-shaft, and which pistons divide space outside the explosion-cylinder 115 into two chambers, one of which serves as the compression-chamber and the other of which serves as a lubricating-chamber, substantially as described.

5. In a two-cycle explosive-engine, the combination of a pair of opposing pistons working in a common explosion-cylinder, controlling, one the exhaust-port and the other the admission-port, of said cylinder, one of which pistons is differential and encircles the crank-shaft, which two opposing pistons are connected to opposing cranks from opposite sides of the crank-shaft, and which pistons divide space outside the explosion-cylinder 130

into a compression-chamber and lubricating-chamber, the contents of which lubricating-chamber are subject to the action of the cranks and the pistons for effecting the distribution of the lubricating-oil to all the working parts of the engine, substantially as described.

6. In a two-cycle explosive-engine, the combination of a pair of opposing pistons working in a common explosion-cylinder, controlling, one the exhaust-port and the other the admission-port of said cylinder, one of which pistons is differential and encircles the crank-shaft, which two opposing pistons are connected to opposing cranks from opposite sides of the crank-shaft, and which pistons divide space outside the explosion-cylinder into two chambers, one of which serves as the compression-chamber having a charging-passage leading to the admission-port of the explosion-cylinder, and which compression-chamber is provided with an inlet-valve for the explosive mixture, substantially as described.
7. In a two-cycle explosive-engine, the combination of a pair of opposing pistons working in a common explosion-cylinder, controlling, one the exhaust-port and the other the admission-port, of said cylinder, one of which pistons is differential and encircles the crank-shaft, which two opposing pistons are connected to opposing cranks from opposite sides of the crank-shaft, and which pistons divide space outside the explosion-cylinder into two chambers, one of which serves as a compression-chamber having a charging-pas-

sage leading to the admission-port of the explosion-cylinder, an inlet-valve for the explosive mixture at the compressing end of said charging-passage, and an air-admission valve at the outer end of said charging-passage, all for coöperation, substantially as described.

8. In a two-cycle explosive-engine, the combination of a pair of opposing pistons working in a common explosion-cylinder, controlling one the exhaust-port and the other the admission-port of said cylinder, one of which pistons is differential and encircles the crank-shaft, which two opposing pistons are connected to opposing cranks from opposite sides of the crank-shaft and which pistons divide space outside the explosion-cylinder into two chambers, one of which serves as a compression-chamber having a charging-passage leading to the admission-port of the explosion-cylinder, an inlet-valve for the explosive mixture at the compressing end of said charging-passage, an air-admission valve at the outer end of said charging-passage and a governing-valve located in said charging-passage directly inward of said mixture-inlet valve, and operative to throttle either the mixture-inlet or said charging-passage, at will, all for coöperation substantially as described.

In testimony whereof I affix my signature in presence of two witnesses.

ELLIS J. WOOLF.
